TYPE SHUTTLE AND ACTUATING
MECHANISM THEREFOR

De Forest F. Neely, Kansas City, Mo.

Application November 8, 1948, Serial No. 58,872

8 Claims. (Cl. 197—49)

1

This invention relates to improvements in type-writing machines and more particularly to type carriers or shuttles of the kind formed to reciprocate freely within a circular anvil having a central slot formed therein for receiving the carrier.

By way of explanation, the subject matter of this invention concerns typewriting machines commonly referred to in the trade as the "Vari-typewriter" and has more specifically to do with the type carrier or font that is used with such typewriting machines, the most important object being to provide a type carrier having an arcuate segment upon which the type itself is formed and a web-like reinforcing and mounting segment, such web-like segment being specially formed for more accurate fitting within the type receiving segment, to present a more positive fit with the finger-like lever of the machine upon which the carrier is mounted, and also formed to ride within the aforesaid anvil with less frictional contact therewith.

Among the broad objects just above set forth is the provision of a type font or carrier having a web-like segment provided with a plurality of transverse opposed corrugations formed therein to the end that the frictional contact surface between the carrier and the anvil supporting the same, is reduced materially.

Explaining further one of the broad objects above set forth, it is an important object of this invention to provide a type carrier having a web-like segment of double thickness at mid-point thereon provided with a polygonal opening for slidably receiving the finger of the actuating lever therefor, all to the end that the grommet structure heretofore used in shuttles of this character might be eliminated.

Another important object of the present invention is to provide a type shuttle having an arcuate type-segment and a web-segment that is fitted within a longitudinal groove formed in the type segment, there being a cooperating notch and rib structure formed on the segments to positively align the two segments when assembly takes place.

A still further object of this invention is the provision of a type font of the above mentioned character having the above mentioned polygonal opening formed in the web-like segment thereof, said opening being provided with a pair of opposed notches for receiving yieldable means in the nature of opposed spring members on the supporting finger for positively positioning the type font in a plurality of selected positions.

2

Other objects of the present invention will be made more clear or become apparent as the following specification progresses, reference being had to the accompanying drawing, wherein:

5 Fig. 1 is a cross sectional view of a portion of a typewriting machine showing the type carrier or shuttle forming the subject matter hereof operably mounted thereon.

10 Fig. 2 is a side elevational view of the type font per se, parts being broken away to reveal details of construction.

Fig. 3 is an enlarged, cross-sectional view taken on line III—III of Fig. 2.

15 Fig. 4 is a top plan view of the web segment of the type carrier showing the same entirely removed from the type segment and prior to formation of the central double thickness portion thereof.

20 Fig. 5 is a detailed cross-sectional view taken on line V—V of Fig. 2.

Fig. 6 is a detailed fragmentary, cross-sectional view taken on line VI—VI of Fig. 4; and

25 Fig. 7 is a fragmentary perspective view of a lever and vertical finger for the typewriting machine for receiving the type font.

The typewriting machine with which the type font or shuttle forming the subject matter hereof is adapted to be used, includes a pair of feed rollers 10 and 12, operably mounted upon a carriage (not shown) for feeding a work-sheet upwardly between a type carrier broadly designated by the numeral 14 and a shiftable hammer 16.

30 This hammer 16 is operated in the conventional manner upon actuation of typing keys to strike the work-sheet and bring the same against any one of a number of letters arranged in three rows 18, 20 and 22.

The type carrier or shuttle 14 is mounted on a ring-like support or anvil 24, said anvil 24 having a slot 26 through which extends a guide web or actuating segment 28, mounted upon a segment 30, which in turn has the rows of type 18, 20 and 22, formed thereon.

35 As shown in Fig. 2 of the drawing, the shuttle 14 is provided with two groups of types at opposite sides of the hammer 16, the shuttle 14 being operable by a lever or actuator 32 from a central position to either side of the machine to carry the desired types to the printing point opposite the hammer 16. This shuttle actuating lever 32 is pivotally supported by a sleeve 34 to swing about a vertical shaft 36 that is suitably supported in the machine frame 38.

40 Lever 32 is provided with a vertical finger 40 that passes through an opening 42 formed in the

55

web-like segment 28. The shuttle actuator 32 is operated by any one of a pair of vertically disposed arms 44 and 46 that are actuated by key levers. Indexing pins 48 are also operable by the key levers to project the same into the path of an arm 50 of the actuator 32 to register the selected type at the printing point.

Heretofore the type carriers or shuttles produced for use with machines of the above mentioned character, have been provided with a web segment 28 of much the same character as shown in Figs. 2 and 4 of the drawing, except that the same included a separate bushing mounted within the opening of the segment 28 and secured thereto by rivets.

It has been found in the field, that such type of formation of the bearing assembly within the web segment 28, is unsatisfactory because of the loose fit presented between the web 28 and the finger 40. Consequently, when the actuator 32 is swung to the extremities of its path of travel, there is a tendency for the shuttle 14 to swing by centrifugal force beyond the desired position, with a consequent misalignment of the type upon the sheet of writing material being used. Through such loose interconnection between the type font and the supporting finger 40, there is also experienced the difficulty of misalignment due to transverse wobbling of the entire font 14 upon the finger 40. Consequently the finished type-written sheet has rows of letters that are out of alignment, not only longitudinally but transversely and obviously, the longer a particular shuttle is used, the more wobble and relative swinging movement takes place between the shuttle and the supporting finger.

These difficulties and others have been met by the construction about to be described. The web 28 is of the usual arcuate contour and formed from an initially flat sheet of metallic material, the same being stamped or otherwise formed to present a laterally extending flap 52 intermediate the ends thereof. This flap 52 extends radially inwardly from the innermost arcuate face of the web 28 midway between the ends thereof. The flap 52 is also provided with a short tab 54 extending outwardly from its outermost free end and the opening 42 for the web 28 is formed by a pair of identical openings 56 and 58 formed in the main body portion of web 28 and within the flap 52 thereof respectively. The flap 52 is folded from the position shown in Fig. 4 of the drawing on a line indicated by the numeral 60 in Fig. 4 to overlap the main body portion of web 28 intermediate the ends thereof. When the flap 52 is so folded, the openings 56 and 58 are in direct mutual alignment and the tab 54 is bent laterally to pass through a polygonal opening 62 formed in the web 28. Consequently, with the tab 54 and the opening 62 correctly positioned, the openings 56 and 58 will be in direct mutual alignment when folding of flap 52 takes place and such openings 56 and 58 will remain in such position throughout the life of the type shuttle.

Fig. 3 of the drawing clearly illustrates the position of tab 54 within opening 62 and after such folding of the flap 52 takes place, the entire metallic web 28 is hardened for assurance that the flap 52 will always remain in the position shown in Figs. 2 and 3 of the drawing.

The over-all length and width of the original opening 42 formed by the aligned openings 56 and 58, is the same as the cross-sectional area as the finger 40 of actuator 32. Consequently, when the shuttle 14 is moved into position upon

the finger 40 in the manner shown in Fig. 1 of the drawing, a relatively tight sliding fit is presented between the shuttle 14 and the finger 40. The double thickness afforded by the flap 52, together with the precise contour of the opening 42, prevents transverse wobble of shuttle 14 upon the finger 40 and by the same token, prevents movement of shuttle 14 longitudinally with respect to finger 40 when the lever 32 is actuated.

Through such construction, the additional parts heretofore needed in providing a separate grommet or bearing is eliminated and a sufficient contacting surface is presented between the web 28 and the finger 40 to prevent all relative movement between such parts. It is obvious also that the cost of production of this type of web 28 is appreciably less and that the same may be produced with speed and dispatch as compared with the shuttle having a separate grommet or bearing for receiving the finger 40. The web 28 and particularly the opening 42 thereof has been produced for use with the present type of machines having fingers formed as at 40 without the necessity of altering the latter, but it is contemplated further that finger 40 be also altered in the manner illustrated in Fig. 7 of the drawing. Such alteration consists of affixing to the finger 40, a pair of opposed springs 64 and 66 of identical character.

These springs 64 and 66 are in opposed relationship and extend longitudinally of the finger 40 and are formed from lengths of resilient wire or the like and bent into a plurality of loops in the manner illustrated in Fig. 7 of the drawing. Such loops of the two spring members 64 and 66 are in direct opposed relationship and the ends of the springs are fused or otherwise fixed directly to the proximal face of finger 40. Through formation of such plurality of loops, a number of depressions 68 are presented on both faces of the finger 40.

In order to accommodate such springs 64 and 66, the opening 42 of the web segment 28 is provided with a pair of opposed V-shaped notches 70 in the longitudinal edges thereof. Obviously, both openings 56 and 58 are so contoured and when the web 28 is mounted upon the finger 40 having springs 64 and 66 thereon, the notches 70 will accommodate such springs. As the shuttle 14 is moved longitudinally with respect to the finger 40, the loops of the spring will compress until such time as the opening 42 is positioned within the recessed portions 68. Accordingly, a positive positioning of the shuttle 14 is presented on the finger 40, there being three depressions 68 corresponding to the three rows of type 18, 20 and 22.

Another reason for the misalignment of type upon the writing paper, lies in the large area of frictional contact between the conventional web of the shuttle and the anvil 24. As the web 28 slides along the opposed guides presented by slot 26, a drag takes place and when the hammer 16 is actuated, the particular type that is struck thereby, will be out of alignment because of the tendency of the shuttle to lag behind the finger 40 and actuator 32. The web 28, therefore, of the present invention is provided with a plurality of opposed corrugations 72 suitably stamped therein during the initial production of web 28.

These corrugations 72 are formed transversely of the web 28 throughout its length in the manner illustrated in Figs. 2 and 4 of the drawing and when web 28 is positioned within the slot 26, only the extremities of the corrugations 72 will

actually be in frictional contact with the opposed sides of the slot 26. This contact is schematically illustrated in Fig. 6 of the drawing by lines 74. The segment 30 of shuttle 14 has heretofore been produced in a number of differing manners such as the use of hard rubber with the rubber vulcanized on a perforated metal segment. In some cases, the guide web was attached to the type segment through the medium of an additional metal segment for reinforcing the type segment.

Another form constituted a molded type segment of phenol condensation with the web of the shuttle bonded upon the type segment during the molding process. In any event, the conventional type segment constituted a plurality of parts requiring precise alignment during the interconnection process and resulting in an expensive and delicate operation.

It has been found in the field that it is almost impossible to align the various parts of the type segment so as to assure alignment of letters upon the writing material and, obviously, the cost of production of such type of shuttle is tremendous.

It is contemplated that the segment 30 of the present device can be manufactured through the use of apparatus in the nature of a hobbing machine of the kind set forth in my copending application, Serial No. 58,873, filed on even date herewith, and entitled "Apparatus and Method for Manufacture of Type Fonts and the Like." Such machine takes the nature of a press having suitable die members as a part thereof capable of forming an initially flat sheet of metallic material into the arcuate contour illustrated in the drawing. Such machine automatically forms the type rows 18, 20 and 22 with the outermost faces thereof positively flat, as illustrated in Fig. 3 of the drawing. During such stamping operation, a plurality of ribs 76 and 78 are formed on the face of the segment 30 opposite to the type.

A longitudinal groove 80 is also formed on this opposite face of the segment 30 between the ribs 78 thereon for receiving the outermost longitudinal edge of the web 28. In order to positively position the web 28 with the opening 42 thereof in the exact center with respect to the segment 30, a rib 82 is formed on the innermost face of the segment 30, said rib extending transversely of the slot 80 and of the ribs 78. This rib 82 is positively positioned at a mid-point between the ends of the segment 30 and is received by a similarly shaped notch 84 formed in the web 28 at its exact center.

During the assembling process, the operator need only assure himself that the rib 82 and notch 84 are in relative engagement and that the web 28 is seated within the longitudinal groove 80 of segment 30.

The final step of the assembling operation constitutes fusing of the web 28 in the groove 80 by a suitable soldering or welding operation that includes preferably a material that will readily flow in groove 80 and fuse the entire outermost longitudinal edge to the segment 30.

It is obvious that the forming of the segment 30 from a single sheet of material and forming the lettering 18, 20 and 22 thereon by a stamping process, is advantageous since there is thereby presented a plurality of letters that are equally spaced not only longitudinally but transversely. All of the letters of the rows 18, 20 and 22 are in direct vertical alignment and there is no difficulty experienced with respect to mis-

alignment during assembling of a plurality of separate parts.

It is apparent from the foregoing that a large number of changes are provided in the type font forming the subject matter hereof over the conventional font, all for the purpose of eliminating the present difficulties with respect to misalignment of the rows of typewritten letters upon the writing material. Such difficulties have been met through cooperation of the precise formation of the web 28, the finger 40 and the segment 30.

It is apparent that many additional changes other than those above set forth, may be made in such printing instrumentalities without departing from the spirit of this invention as defined by the scope of the appended claims.

Having thus described my invention, what I claim as new and desire to secure by Letters Patent is:

1. A type shuttle for a typewriting machine comprising a type segment and a web-like member thereon, said member having a plurality of ribs formed thereon to provide sliding surfaces for the member when the same is moved along a guide therefor.

2. A type shuttle for a typewriting machine comprising a type segment and a web-like member thereon, said member having a plurality of ribs formed thereon to provide sliding surfaces for the member when the same is moved along a guide therefor, said ribs traversing the path of travel of said member on said guide.

3. A type shuttle for a typewriting machine comprising a type segment and an arcuate, web-like member thereon, said member having a plurality of substantially radial ribs formed thereon to provide sliding surfaces for the member when the same is moved along a guide therefor.

4. A type shuttle for a typewriting machine comprising a type segment and a web-like member thereon, said member having a plurality of ribs formed thereon to provide sliding surfaces for the member when the same is moved along a guide therefor, said ribs extending outwardly from the opposed faces thereof.

5. A type shuttle for a typewriting machine comprising a type segment and a web-like member thereon, said member having a plurality of opposed corrugations formed therein to provide sliding surfaces for the member when the same is moved between a pair of spaced guides therefor.

6. A type shuttle for a typewriting machine comprising an arcuate type segment formed from a single strip of metallic material and having a longitudinal groove formed in the innermost face thereof; and a web-like member fitted in said groove and secured to the type segment, said face of the type segment having a centrally-disposed rib intersecting said groove thereof, said member being notched midway between the ends thereof for receiving said rib.

7. In a typewriting machine, the combination of an elongated finger; a type carrier having an apertured, web-like member as a part thereof, said aperture receiving the finger for longitudinal sliding movement of the member on the finger; and means on the finger for yieldably holding said member in a number of selected positions on the finger.

8. In a typewriting machine, the combination of an elongated finger; a type carrier having an apertured, web-like member as a part thereof, said aperture receiving the finger for longitu-

dinal sliding movement of the member on the finger; and means on the finger for yieldably holding said member in a number of selected positions on the finger, said means comprising at least one elongated spring secured longitudinally on the finger and formed to bias toward the proximal edge of said aperture when the member is on the finger.

DE FOREST F. NEEDLY.
